AUTOMOTIVE REAR VIEW MIRROR

Sol H. Lapidus, Great Neck, N.Y., assignor to Blue Fox Industries, Inc., Brooklyn, N.Y.

Filed Aug. 4, 1971, Ser. No. 169,166

Term of patent 7 years

Int. Cl. D12—08

U.S. Cl. D14—6 M

Fig. 1

Fig. 2

Fig. 3

Fig. 4

Fig. 5

FIG. 1 is a front elevational view of an automotive rear view mirror showing my new design;

FIG. 2 is a rear elevational view thereof;

FIG. 3 is a top plan view thereof;

FIG. 4 is a bottom plan view thereof; and

FIG. 5 is a side elevational view thereof, the opposite side being symmetrical.

I claim:

The ornamental design for an automotive rear view mirror, substantially as shown and described.
